MACHINE FOR GRINDING METAL

Edgar Bannister, London, England, assignor to
D. Gilson and Company Limited, London, Eng-
land, a company of Great Britain

Application October 28, 1942, Serial No. 463,682
In Great Britain November 29, 1941

20 Claims.

(Cl. 51—33)

The invention relates to machines for grinding metal surfaces, and has particular reference to the grinding of the lands of screw dies of the so-called "button" type.

In finishing screw dies, particularly those made for precision work, it is necessary to grind accurately the leading face of each land. In order to produce the best cutting edge, the angle of the leading face to the radial line passing through the cutting edge must be accurately defined, although it may be different for dies for cutting different metals. It is also important that the leading faces of the different lands shall be equally spaced angularly around the die, that is to say, in the case of a 4-land die, for example, the leading edges must be accurately spaced 90° apart; furthermore, of course, the leading edges must all be equally spaced from the centre of the die. These latter two requirements are necessary if all the lands are to do the same amount of work and screw-threads of the accuracy necessary in precision work are to be cut.

For this final finishing by grinding, it is fairly usual nowadays to use a small grinding wheel of a suitable abrasive material which has to be of small diameter in relation to its length so that it takes the shape of a pencil which is rotated accurately about its axis at very high speed. A convenient form of such a grinding wheel is what is called an air-driven pencil since it is rotated at high speed by compressed air acting on what amounts to a small air turbine, the rotor of which is on the rear end of the grinder spindle. If the die to be finished is mounted in a holder and the grinding pencil is on a carriage or support which is moved by hand by the operator while the pencil can be reciprocated in the direction of its axis, it is clear that the accuracy of the finished job depends almost entirely on the skill of the operator.

The object of the present invention is to produce a precision machine which can be used by an unskilled or relatively unskilled operator and yet produces accurately in every die the necessary conditions which have been set out above.

According to the present invention, such a grinding machine is provided with a die holder in which the die to be finished can be fixed in a horizontal position, and in order to produce the cutting feed, the die is rotated the necessary small amount about its axis and the total amount of that feed can be predetermined since the rotation is effected by the operator turning a wheel or handle until the handle or a part integral with it is brought up against a stop which is pre-ad-

justed to fix the amount of feed. Then the actual shape of the leading edge of each land of the die is determined by mounting the grinding pencil on a pantograph mechanism, furnished with a stylus which the operator keeps in contact with an enlarged copy of the desired leading face. For convenience it can be arranged that the operator rotates the die slightly by turning the feed handle with his right hand while the support for the enlarged copy and the stylus are arranged to the left-hand side of the machine so that the stylus is readily operated by the attendant's left hand.

It is common to make dies with three, four, 15 or five lands, and in the larger sizes a greater number of lands are often produced. Therefore, when the leading face of one land has been ground, it is necessary to be able to rotate the die in its holder accurately through the desired angle—which in the case of a four-land die is an angle of 90°—so that the leading face of the next land can be shaped accurately to the same shape as the first land but at an angle around the die which is exactly 90° in the example of a four-land die with respect to the leading face of the first land. To facilitate this procedure, the die holder is provided with a registering device which can hold it accurately in a number of positions spaced apart by the necessary angle depending upon the number of lands. The registering device may consist of the appropriate number of recesses in the periphery of the holder engaged by a pivoted tooth carried on the holder although, of course, the converse arrangement might be employed. Between the feed handle which may rotate the die holder through worm gearing, and the die holder itself, a one-way clutch which may conveniently be a roller clutch without backlash, is provided. Then, as the cut is applied by rotating the die holder, owing to the shape of the recess and the engaging tooth, the latter is gradually forced out of the recess until it rides on the periphery of the holder, the drive being through the aforesaid one-way clutch. Then, by 25 rotating the die holder in the same direction so that the clutch overrides, the tooth can be caused to enter the recess corresponding to the next land and the die then is in position accurately displaced from the first position through the required angle ready for making a similar cut on the leading face of the next land. On turning the feed handle back to its initial position in readiness for making the cut on the next land, the die cannot be displaced due to friction in the clutch 30 because the die holder is held by the tooth and

recess. The procedure is then repeated until all the lands have been similarly accurately ground.

In such a machine the grinding pencil, of course, is subject to slight wear and after a time the surface tends to become glazed. It is necessary to be able to dress the grinding pencil, and the present invention provides for that dressing while compensating for the slightly reduced diameter of the grinding pencil without loss of accuracy in the grinding. For that purpose, the die holder is mounted on a cross-slide with an operating wheel properly indexed which enables the die holder to be moved slightly across the machine. The dressing diamond is provided merely with a holder the body of which can be set in the machine in the die holder in such a position that when the grinding pencil is centred in the machine, which can be effected by inserting a locking taper pin in the pantograph mechanism, the pencil, before it has been reduced in diameter, takes up a central position in a central bore in the dresser body and can be rotated therein. The diamond carrier is set radially in the body so that it can be brought accurately up to the surface of the grinding pencil for the dressing feed. For that purpose, a pin of the same diameter as the grinding pencil is introduced through a bore at the top which it fits accurately and the diamond is set accurately just in contact with the pin which is then withdrawn. The grinding pencil is then brought up into the central position and the cross-slide referred to is advanced the necessary amount and the diamond takes a slight cut on the periphery of the grinding pencil. If no further provisions were made and the grinding of the die were proceeded with, it is obvious because of the reduced diameter of the grinding pencil that the next cut would be slightly less deep than the immediately preceding cut before the grinding pencil were dressed. This is corrected or compensated for, however, by leaving the die holder in the slightly adjusted position it has been given by means of the cross feed so that in effect the die has now been slightly placed out of centre relative to its previous position by an amount equal to the cut taken off the surface of the grinding pencil. Thus, when grinding next proceeds, owing to this adjustment of the die, the next land of the die will be cut in exactly the same way as the preceding land is cut.

For convenience in such a machine, the grinding pencil is not given a vertical reciprocation at all, but when the pantograph is unlocked, it can only move in a horizontal plane in accordance with the shape of the pantograph copy-piece. The die holder, however, is mounted on a carrier which includes the worm mechanism for producing the feeding cut, and this carrier is mounted so as to be capable of vertical reciprocation under the action of cams on a cam shaft which extends from right to left across the machine below the carrier.

In order that the invention may be clearly understood and readily carried into effect, a machine in accordance with the invention designed for grinding a four-land button die will now be described by way of example with reference to the accompanying drawings, in which:

Figure 1 is a perspective view of the outside of the complete machine;

Figures 2 and 2a show a plan of the machine, Figure 2 depicting the left-hand side, and Figure 2a the right-hand side of the machine;

Figures 3 and 3a show a vertical section on the

line III—III in Figure 2, Figure 3 again illustrating the left-hand side of the machine, and Figure 3a the right-hand side of the machine;

Figure 4 is an elevation of the machine seen from the right of Figure 3, the view being shown partly in section on the line IV—IV in Figure 3a;

Figure 5 is a perspective view showing the main parts of the pantograph linkage employed;

Figure 6 is a vertical section showing the main pivots of the pantograph;

Figure 7 is a central vertical section of the die holder and its driving mechanism, and also showing the grinding pencil;

Figure 8 is a horizontal section on the line VIII—VIII in Figure 7;

Figure 9 is an elevation of a detail seen from the front of the machine in the direction of the arrow X in Figure 4;

Figure 10 is an elevation, with the lower part in section, of the compressed air motor for the grinding pencil;

Figure 11 is a diagram to an enlarged scale of a die to be ground;

Figure 12 is a further diagram still more enlarged, illustrative of the process of grinding;

Figure 13 is a section similar to Figure 7 but showing the pencil dressing tool in position;

Figure 14 is an elevation of a gauging appliance for use with the diamond tool used in dressing the grinding pencil shown in position in the tool; and

Figure 15 is a horizontal section on the line XV—XV in Figure 13.

Referring first of all to Figures 1 to 4, the machine shown as an example is a small bench machine housed in a casting 1 and driven by a small electric motor 2, whose shaft 3 runs from the back of the machine towards the front at the right-hand side of the machine, as best seen in Figure 2a. The motor 2 drives a worm 4 and a worm wheel 5, which latter is carried by a sleeve 6 which is journalled to turn about a cam shaft 7 of the machine which runs transversely across the machine from the right-hand side. The movable member 8 of a dog clutch is keyed to the shaft 7 and can be shifted to the right in Figure 3a to clutch the cam shaft 7 to a hand wheel 9. The member 8 also has dog teeth on its opposite or left-hand side in Figure 3a which, when the member 8 is moved to the left, clutches the cam shaft 7 to the driven sleeve 6 so that the machine can be turned slowly by hand by the hand wheel 9 or can be power driven. The clutch member 8 is actuated by a control lever in the form of a joystick 10 mounted for transverse movement from left to right of the machine, and for fore-and-aft movement from back to front of the machine. During the transverse movement it has three definite positions located by spring-pressed balls 11 (Figure 4). When the joystick 10 is moved to the left into the position 10a shown in Figure 2a, it rocks a fork 12 to cause the clutch member 8 to engage the sleeve 6. When the joystick is in the middle position, the clutch member 8 is disconnected, and when it is moved to the right-hand position shown at 10b in Figure 2a, the clutch member 8 is connected to the hand wheel 9. During the fore-and-aft movement of the joystick 10, a valve 13 controlling the supply of compressed air to the grinding wheel mechanism is operated. Compressed air is supplied through a pipe 14 and the valve 13 controls its passage to a flexible pipe 15 which is connected to the air motor for the grinding pencil, as will

lower end at 16, and when in the full line position shown at 10 in Figure 4, the valve 13 is pushed backward from the position shown in Figure 2a to shut off the connection between the pipes 14 and 15. When the joystick is turned into the position shown in dotted lines at 10c in Figure 4, the valve 13 is moved into the position shown in Figure 2a to allow the supply of compressed air to pass to the machine through the pipe 15. The lever 10 moves between the lugs 216 of its pivot bracket and these lugs are furnished with pins 217 for indexing it in its fore-and-aft positions 10c, 10.

The grinding wheel mechanism seen in Figure 3a but shown in detail in Figure 10, comprises a casing 17 mounted on and extending upwards from a bracket 17a carried on a horizontal link 18 of the pantograph linkage. The grinding wheel assembly can be adjusted from back to front of the machine on a slide 19 on the link 18 and is locked in the adjusted position by means of a set-screw 20. The compressed air pipe 15 is connected to an inlet nipple 21 communicating with a passage 22 in the base 23 of the grinding wheel mechanism. The passage 22 is continued as a nozzle 24 in a plate 25 so that jets of air are injected into the blades of a bladed wheel 26. The wheel 26 is fixed to the lower end of the spindle 27 of the grinding wheel or pencil 28 and which is a cylindrical pencil of emery or other abrasive composition. The spindle 27 is journalled in the casing 17 and the air escaping from the wheel 26 passes upwardly through the casing 17, as indicated by the arrows 29 in Figure 10, and therefore serves the purpose of cooling the bearings of the spindle 27 and also of blowing away any fine dust removed from the die under treatment by the grinding pencil 28.

The pantograph linkage is best seen in Figures 2, 2a, 3, 3a, 5 and 6. It consists of a parallelogram linkage consisting of two pairs of parallel links 18, 30, 31, 32, hinged together at the corners. As already stated, the grinding wheel mechanism is mounted on the link 18 which is hinged to the link 31 about a pivot 33. This pivot, as shown in Figure 6, is offset from another pivot 34 which is the main fulcrum of the mechanism and is set in the bottom plate 35 of the machine. The link 30 is steadied by means of a pair of auxiliary links 36, 37, the link 36 being pivoted at 38 to the pantograph link 30 and at 39 to the link 37, the latter being pivoted to the bottom plate 35 at the point 40. The upper link 18 is also steadied in a similar way by a pair of links not shown in Figure 5, but one of which appears at 41 in Figure 3a, and turns about a vertical pivot fixed to the casing of the machine, and also pivoted to a second link which in its turn is pivoted to the bracket 17a secured to the pantograph link 18. The stylus or tracing point 42 is carried in a head 43 which can be adjusted along a rod 44 and secured in position by a locking screw 45. The rod 44 is rigidly fixed by a bracket 46 in line with the centre of the link 32. It will, therefore, be seen that by moving the tracing point 42, the linkage 18, 30, 31, 32, turns freely about the main fulcrum pivot 34, and the different links can turn about the pivots which form the hinges between each pair of links. The equivalent pantograph mechanism is indicated by the three lines 47, 48 and 49 in Figures 2 and 2a. The intersecting point 50 between the lines 47 and 48 represents the position of the axis of the main fulcrum 34 of the pantograph linkage. The axis of the pencil 28 is located at the point 51 in the centre line of the link 18. As already men-

tioned, the point 51 can be adjusted between the back and the front of the machine along the slide 19, and the effective length of the arm 32, 43, 44 can be adjusted by unlocking the head 43 by the screw 45 and sliding the head 43 on the rod 44. In this way, the ratio of the amount of movement of the tracing point 42 to that of the grinding pencil 28 can be altered to some degree. The tracing point 42 is arranged to be moved over a small table 52 secured to the casting of the machine and arranged to carry a copy-piece or pattern 53 which has a rib 54 which bears the same profile as the faces of the die to be ground. When the pantograph linkage is shifted so that the grinding pencil 28 takes up a central position within the die holder, the pantograph linkage can be locked in that position by the insertion of a tapered plug 55 into holes in the main casting 1 and passing through a hole in the rod 44, as seen in Figures 2 and 3. The grinding pencil 28 is only able to move in a horizontal plane under control of the tracing point 42 of the pantograph mechanism and is not mounted for up and down movement in a vertical plane.

On the other hand, the die holder shown in detail in Figures 7 and 8 is mounted to slide up and down, being fixed to two supporting pillars 56, 57 whose axes lie on the transverse centre line of the die holder, as can be seen in Figure 2a, and a front central steady column 58 which is merely guided in guides 59 in the framework casting of the machine so as to prevent any rocking of the die holder when the latter is raised or lowered. The die holder is raised and lowered by means of the pillars 56 and 57 which are cam-operated from the cam shaft 7. This mechanism is seen best in Figures 3a and 4. Each of the pillars 56, 57 has at the lower end an adjustable tappet-like member 59, 60, adjustable by means of screws 61, 62 and locked in the adjusted position by lock nuts 63, 64. The tappets 59, 60 have large heads which rest on operating rollers 65, 66, as best seen in Figure 4. Each of these rollers is carried at the free end of an arm 67 pivoted towards the back of the machine at 68 and each of the arms at its mid-length has a roller or cam follower 69 which rests on the respective cam 70 on the cam shaft 7. The cams 70 are of the same shape and operate in unison to lift the arms 67 together so that the rollers 66 lift the pillars 56, 57 and with them the whole die holder assembly. The latter descends under its own weight or under spring tension which retains the tappets 59, 60 in contact with the rollers 65, 66.

The whole of the die holder assembly, including the pillars 56, 57, the guides 71, 72 in which they slide, and the steady pillar or column 58, and the guide 59 in which it slides, is mounted on a slide on the machine bed by means of which the assembly can be moved slightly from right to left of the machine. The sliding surfaces are seen at 73 in Figure 4, and the usual packing gibs are shown at 74. The sliding movement is effected by a screw-threaded spindle 75 carrying an index wheel 76, the latter bearing against a surface 77 on the main frame casting 1, and the threaded spindle 75 engaging a threaded nut member 78 which is rigid with the die holder assembly. Accordingly, by rotating the hand wheel 76, the whole of the assembly is moved to the right or left on the sliding surfaces 73 by a predetermined amount. A locking screw for this slide is provided at 79 and this naturally has to be slackened back before the die holder assembly can be moved. The die holder assembly is set into a zero position when the grinding pencil is new and has not

been dressed, so that under those conditions, when the pantograph linkage is locked by means of the tapered plug 55, the axis of the grinding pencil 28 coincides with the central axis of the die holder.

The die holder proper is a tubular member 80 (Figures 3a and 7) with an inwardly projecting ledge or shoulder 81, the internal diameter of the member 80 being of such a size as to accommodate the largest die to be finished. Such a die is shown in position in Figures 3a and 7 at 82. In order to enable smaller dies to be ground, adapters may be employed which can be fitted in the die holder 80 on the shoulder 81, and each having an internal bore of a size to receive a particular size of die. A die to be operated upon is placed in the holder 80 and is prevented from rotation therein by a tongue or projection 83 on the member 80 engaging a recess 84 in the periphery of the die. However, the die holder as a whole can be rotated within its mounting 85 and for that purpose it is connected to an outer ring 86 through a one-way clutch of the roller type which is designed to avoid any lost motion or backlash. This clutch is constituted by a number of vertical rollers 87 (Figs. 7 and 8) which are housed in wedge-shaped recesses 88 in the outer ring 86 and are engaged by the outer surface of the tubular die holder 80. The result is that if the outer ring 86 is driven in a counter-clockwise direction, as indicated by the arrow 89 in Figure 8, the rollers 87 assisted by light springs 90 are wedged into the narrow parts of the wedge-shaped recesses 88, and the die holder 80 is driven in the same direction. When the outer ring 86, however, is turned clockwise, the rollers 87 are released and the die holder 80 remains stationary. The outer ring 86 is formed with worm teeth 91, as seen in Figure 7, which are engaged by a worm 92 on a spindle 93 running from back to front of the machine. The worm 92 is rotated by means of a crank handle 94 fixed to the front end of the worm spindle 93, and the arrangement is such that the die holder 80 is rotated in the manner described above through the one-way clutch rollers 87 when the crank handle 94 is turned clockwise, but when the handle 94 is turned back, the die remains stationary.

The details of the crank handle arrangement are best seen from Figure 9. The crank handle 94 is furnished with a rearwardly extending arm 95 which has stop surfaces 96, 97 on opposite sides, and in such a position that when the crank handle 94 is turned counter-clockwise, a stop surface 97 makes contact with a fixed but adjustable stop member 98, while when the crank handle 94 is turned clockwise in the direction of the arrow 99, the stop surface 96 will be brought into contact with the upper surface of a second fixed but adjustable stop member 100. The stop members 98 and 100 can be adjusted around on the dovetail-shaped rim 131 of a stationary disc 132 best seen in Figure 2a, and when the stop members 98 and 100 have reached the desired positions, they can be fixed on the rim 131 by a pair of pinching screws 133, 134. When the crank handle is turned back counter-clockwise so that the surface 97 is in contact with the member 98, the crank handle 94 is in its starting position, and as already explained, although the worm 92 is then rotated, the die holder 80 remains stationary because the clutch rollers 87 permit of slipping. The operator can turn the crank handle 94 clockwise by a predetermined amount defined by the position of the second stop member 100, whereupon the stop surface 96 comes into contact

with the stop member 100, and during that movement the clutch rollers 87 are in driving engagement so that the die holder 80 is gradually rotated. Actually, as will be explained below, that rotation of the die holder represents the total amount of feed which the operator can carry out with a given setting of the stop member 100.

In order to describe the operation of the machine, it should be realised that as so far described, the die 82 to be finished is set in the die holder as shown in Figures 3a, 7 and 8, with the recess 84 engaged by the tongue 83 so that the die is constrained to rotate with the die holder 80. The die holder 80 is formed with a flanged rim 101 which is formed with a number of recesses 102, and in fact, as shown, there are four of these recesses spaced at 90° and corresponding to the four lands 103 of the die which is being ground. Each of the recesses 102 is in a position to be engaged by a retaining tooth 104 on the end of a bell crank lever 105 pivoted at 106 and controlled by a spring 107 so that the tooth 104 tends to enter a recess 102 when the latter is brought round into a position opposite the tooth 104. The latter therefore serves to register the die holder in a given angular position. At this stage it is necessary to describe in greater detail the operation which it is desired to perform upon the lands of the die. Thus, referring to Figures 11 and 12, in Figure 11 the die 82 is shown to an enlarged scale. It is drilled with a central hole as indicated by the faces 108 of the lands 103, and that central hole is tapped with the required screw-thread. Then the lands 103 are formed by drilling the four holes 109 in such positions that these holes just break into the central hole 108, as can be readily seen from Figure 11. The grinding which has to be effected is to take away the sharp leading corner of each land, that is to say, that the metal indicated at 110 which remains after drilling or any other machining operation such as broaching, has to be ground back to the cross-hatched lines shown at 111. In order to illustrate this more clearly in Figure 12, the lowermost hole 109 is shown to yet a larger scale, the face of the adjacent land being shown at 108 as in Figure 11. The sharp corner which has to be ground away is shown by the line 110, and the surface to which the land is to be finished is again shown by the cross-hatched line 111, so that it is the metal between the lines 110 and 111 which has to be removed during the grinding operation. The grinding pencil 28 is shown in full lines at one of its extreme positions and in chain lines at successive positions as it is moved by causing the tracing point 42 of the pantograph mechanism to follow the rib 54 of the pattern, and indeed the curve 112 shows the path followed by the centre line of the grinding pencil when the tracing point 42 is gradually moved along the rib 54. It is intended that while the operator is manipulating the tracing point 42 with his left hand, he should gradually turn over the feed crank handle 94 with his right hand, and when he moves this handle from the starting position shown in Figure 9 clockwise in the direction of the arrow 99, the die holder 80 and the die 82 are moved gradually as indicated by the arrow 113 in Figure 12. In other words, the face of the land 103 is pushed up against the grinding pencil 28 and gradually the metal between the lines 110 and 111 in Figure 12 is removed by the grinding pencil 28.

At the beginning of the operation the retaining tooth 104 is engaging one of the recesses 102, as shown in Figure 8, and the control lever 10

has been moved fore-and-aft to admit the supply of compressed air to the grinding pencil assembly as already indicated, and the cam shaft 1 of the machine has been clutched to the driving motor by moving the control lever 10 into the left-hand position 10a in Figure 2a, with the result that the grinding pencil 28 is rapidly rotated and the die holder 80 carrying the die 82 is reciprocated up and down so that grinding on the leading face of the land of the die goes on. This process is continued until the stop surface 96 on the arm 95 (Figure 9) reaches the predetermined stop member 100, at which time it is known without any exercise of skill on the part of the operator that the grinding cut has been taken to the desired depth and exactly the correct amount of metal between the lines 110 and 111 in Figures 11 and 12 has been removed.

It will be observed that one face of each of the recesses 102 is shown in Figure 8 to be more inclined than the other so that as the die 82 is rotated counterclockwise in Figure 8 and the feed goes on, the tooth 104 is gradually forced out of the recess 102 with which it is engaging, and finally the point of the tooth 104 has been rocked outwards into the position shown at 104a in Figure 8 when it comes to rest on the cylindrical peripheral wall of the flange 101 of the die holder 80.

The die holder 80 carrying the die 82 can now be turned in the direction permitted by the clutch rollers 87, that is to say, counter-clockwise in Figure 8, by means of the milled rim 114 until the retaining tooth 104 engages the next recess or notch 102a in the flange 101 of the die holder 80. At this stage the feed crank handle 94 can be turned back counter-clockwise to the initial position shown in Figure 9, during which the one-way clutch rollers 87 slip and the die is not rotated. In the example illustrated of a four-land die, the notch 102a now engaged by the tooth 104 is exactly at 90° to the notch shown engaged by the tooth 104 in Figure 8, so that the machine is ready for a similar grinding cut on the next land of the die, and indeed the cut is made exactly at 90° from that made on the first land. It is made of exactly the same shape due to the use of the pattern 54 and to exactly the same depth due to the permitted traverse of the crank feed handle 94. Therefore, when all four lands have been ground, their leading faces are ground to exactly the same shapes and any point on the face of the one land is spaced exactly at 90° from the corresponding point on the next land so that an entirely uniform and satisfactory finish is produced on the die.

In the drawings, the die is prevented from moving in the holder 80 from the shelf 81 by a tubular clamping member 115 which can be inserted into the holder on top of the die 82. It has a number of peripheral projections 116 which can enter the die holder through slots 117 (Figure 2a), and on rotating the clamping member 115 by handles 118, the projections 116 enter cam grooves 119 with inclined upper surfaces so that the clamping member 115 is firmly pressed down on the top of the die 82.

After a certain number of operations, the grinding pencil 28 has become glazed and its surface needs redressing. Then the die 82 is removed from the holder 80 and a wheel dresser is inserted in its place. This is illustrated in Figures 13 to 15, in which the same references have been used for corresponding parts as in Figures 7 and 8. The wheel dresser consists of a body 120 of the same shape externally as a die and with

a recess which can be engaged by the tongue 83 to prevent rotation of the wheel dresser 120. The wheel dresser 120 has a radial passage to receive the tool 121 which bears the diamond point 122 at its forward end. The pantograph linkage is locked, as already described, so that the grinding pencil 28 takes up a central position in the bore 123 in the body of the wheel dresser 120. The diamond point 122 is set in the correct position by aid of the gauge 125 which is inserted into the wheel dressing tool 120 which is formed with an upwardly extending boss 126 centrally bored to receive the gauge 125 as shown in Figure 14. The point 122 of the diamond is just brought up to the outer surface of the stem 127 of the gauge 126 and then the diamond is locked in that position by a set-screw 124. The gauge 125 is removed and the wheel dresser 120 placed in the die holder 80 and clamped into position by the clamping sleeve 115. Then the grinding pencil 28 is set into rotation by admitting the compressed air supply and the machine set into operation. The grinding pencil 28 is moved slowly to the left in Figures 13 and 15 by moving the whole of the die holder assembly to the left by unlocking the screw 79 and operating the indexing wheel 76 so that the whole of the die holder assembly moves on the slide surfaces 73.

During this sliding movement the tappet heads 59, 60 remain in engagement with the rollers 65, 66 since the tappet heads are made large enough to ensure this.

When the grinding pencil 28 is sufficiently dressed, the wheel dresser is removed from the die holder and the transverse slide is left in the position which it has reached and is locked in that position by tightening the screw 79. The result is that when the die or a fresh die is placed in the die holder, it is slightly displaced in position from that which a die occupied before the grinding pencil was dressed by an amount equal to the cut taken off the wheel in the dressing operation by the diamond 122. Therefore, when grinding of the die is resumed or a fresh die is ground, the grinding pencil 28, although slightly reduced in diameter, takes exactly the same cut upon operating the crank handle 94 which it would have taken if it had not been reduced in diameter and the die holder had not been moved transversely.

The invention has been illustrated and described with particular reference to the grinding and finishing of a button type screw die with four lands spaced at 90° apart, but it is clear that the machine by use of a suitable work holder, can be used for grinding any metal parts that require a similar finish. Thus, for example the invention is applicable to the grinding of the internal teeth of annular gears.

I claim:

1. In a machine for grinding the lands of button screw dies, the combination of a die holder mounted for rotation about the axis of a die carried in said die holder, a spindle journaled to rotate about an axis parallel to that of said die holder, a grinding tool mounted on said spindle, a support carrying said spindle for rotation about said axis, power means operatively connected with said spindle for rotating same, means for moving said support to effect movement of said grinding tool along a predetermined path conforming to the profile to be ground, a rotary feed handle, stop members mounted in the path of said handle for limiting the movement of same in both directions, and gearing connecting said

feed handle to said die holder to rotate the latter about the axis of the die to produce the cutting feed during grinding.

2. In a machine for grinding the lands of button screw dies, the combination of a die holder mounted for rotation about the axis of a die carried in said die holder, a spindle journaled to rotate about an axis parallel to that of said die holder, power means for rotating said spindle, a pantograph linkage provided with a tracing stylus, a support for said spindle mounted on one member of said pantograph linkage, a pattern support located in position to be traversed by said tracing stylus, and manual means for rotating said die holder about the axis of the die to produce the cutting feed during grinding.

3. In a machine for grinding the lands of button screw dies, the combination of a die holder mounted for rotation about the axis of a die carried in said die holder, a spindle journaled to rotate about an axis parallel to that of said die holder, power means for rotating said spindle, a pantograph linkage provided with a tracing stylus, a support for said spindle mounted on one member of said pantograph linkage, a pattern support located in position to be traversed by said tracing stylus, a rotary feed handle and gearing connecting said feed handle to said die holder to rotate the latter about the axis of the die to produce the cutting feed during grinding.

4. In a machine for grinding the lands of button screw dies, the combination of a die holder mounted for rotation about the axis of a die carried in said die holder, a spindle journaled to rotate about an axis parallel to that of said die holder, a support for said spindle, power means for rotating said spindle, means for moving said support to effect movement of said spindle along a predetermined path conforming to the profile to be ground, a rotary feed handle, gearing connecting said feed handle to said die holder to rotate the latter about the axis of the die to produce the cutting feed during grinding, and an adjustable stop located to co-act with said feed handle to limit the maximum amount of the cutting feed.

5. In a machine for grinding the lands of button screw dies, the combination of a die holder mounted for rotation about the axis of a die carried in said die holder, a spindle journaled to rotate about an axis parallel to that of said die holder, power means for rotating said spindle, a pantograph linkage provided with a tracing stylus, a support for said spindle mounted on one member of said pantograph linkage, a pattern support located in position to be traversed by said tracing stylus, a rotary feed handle, gearing connecting said feed handle to said die holder to rotate the latter about the axis of the die to produce the cutting feed during grinding, and an adjustable stop located to co-act with said feed handle to limit the maximum amount of the cutting feed.

6. In a machine for grinding the lands of button screw dies, the combination of a die holder mounted for rotation about the axis of a die carried in said die holder, a spindle journaled to rotate about an axis parallel to that of said die holder, a support for said spindle, power means for rotating said spindle, means for moving said support to effect movement of said spindle along a predetermined path conforming to the profile to be ground, a rotary feed handle, gearing connecting said feed handle to said die holder to rotate the latter about the axis of the die to

produce the cutting feed during grinding, and a one-way clutch interposed between said feed handle and said die holder to permit said die holder to turn forwardly while said feed handle is stationary.

5 7. In a machine for performing a plurality of grinding operations at spaced angular positions on a metal work-piece, the combination of a stationary machine frame, a work-holder mounted for rotation in said frame, a grinding wheel spindle journaled to rotate about an axis parallel to that of said work-holder, a support for said spindle, power means for rotating said spindle, a work-holder registering device comprising a resiliently actuated pivoted tooth located to engage a notch in each of a plurality of angular positions of said work-holder, means for moving said support to effect a predetermined relative movement between said spindle and said work-holder in each of the angular positions of said work-holder and manual means for rotating said work-holder to produce the cutting feed during each of a plurality of grinding operations.

25 8. In a machine for grinding the lands of button screw dies, the combination of a stationary machine frame, a die holder mounted for rotation in said frame and furnished with a plurality of angularly spaced peripheral notches, a grinding wheel spindle journaled to rotate about an axis parallel to that of said die holder, a support for said spindle, power means for rotating said spindle, a resiliently actuated pivoted tooth located to engage in each of said notches to register said die holder in a plurality of angular positions, means for moving said support to cause a predetermined relative movement between said spindle and said die holder in each of the angular positions of the latter, and manual means for rotating said die holder to produce the cutting feed during each of a plurality of grinding operations.

45 9. In a machine for grinding the lands of button screw dies, the combination of a stationary machine frame, a die holder mounted for rotation in said frame and formed with a peripheral rim furnished with a plurality of angularly spaced notches, a grinding wheel spindle journaled to rotate about an axis parallel to that of said die holder, a support for said spindle, power means for rotating said spindle, a rotary feed handle, gearing connecting said feed handle to said die holder to rotate the latter about the axis of the die to produce the cutting feed during grinding, a resiliently-actuated tooth pivoted to said machine frame in position to engage each of said notches to register said die holder in a plurality of angular positions and means for moving said support to cause a predetermined relative movement between said spindle and said die holder in each of the angular positions of the latter.

60 10. In a machine for grinding the lands of button screw dies, the combination of a stationary machine frame, a die holder mounted for rotation in said frame and formed with a peripheral rim furnished with a plurality of angularly spaced notches, a grinding wheel spindle journaled to rotate about an axis parallel to that of said die holder, a support for said spindle, power means for rotating said spindle, a rotary feed handle, gearing connecting said feed handle to said die holder to rotate the latter about the axis of the die to produce the cutting feed during grinding, a resiliently-actuated tooth pivoted to said machine frame in position to engage each of said notches to register said die holder in a plurality

of angular positions, means for moving said support to cause a predetermined relative movement between said spindle and said die holder in each of the angular positions of the latter, and an adjustable stop located to co-act with said feed handle to limit the maximum amount of the cutting feed.

11. In a machine for grinding the lands of button screw dies, the combination of a stationary machine frame, a die holder mounted for rotation in said frame and formed with a peripheral rim furnished with a plurality of angularly spaced notches, a grinding wheel spindle journaled to rotate about an axis parallel to that of said die holder, a support for said spindle, power means for rotating said spindle, a rotary feed handle, gearing connecting said feed handle to said die holder to rotate the latter about the axis of the die to produce the cutting feed during grinding, a resiliently-actuated tooth pivoted to said machine frame in position to engage each of said notches to register said die holder in a plurality of angular positions and means for moving said support to cause a predetermined relative movement between said spindle and said die holder in each of the angular positions of the latter, each of said notches being shaped on one face to cause disengagement of said resiliently-actuated tooth during the rotation of said die holder by said feed handle to produce the cutting feed during each of a plurality of grinding operations.

12. In a machine for grinding the lands of button screw dies, the combination of a stationary machine frame, a die holder mounted for rotation in said frame and formed with a peripheral rim furnished with a plurality of angularly spaced peripheral slots, a grinding wheel spindle journaled to rotate about an axis parallel to that of said die holder, a support for said spindle, power means for rotating said spindle, a resiliently-actuated tooth pivoted in said machine frame in position to engage each of said notches to register said die holder in a plurality of spaced angular positions, means for moving said support to cause a predetermined relative movement between said spindle and said die holder in each of the angular positions of said die holder, a rotary feed handle, gearing connecting said feed handle to said die holder to rotate the latter about the axis of the die to produce the cutting feed during grinding and a one-way clutch interposed between said feed handle and said die holder to permit said die holder to turn forwardly while said feed handle is stationary, each of said notches being shaped on one face to cause disengagement of said resiliently-actuated tooth during the rotation of said die holder by said feed handle in effecting each of a plurality of grinding operations.

13. In a machine for grinding the lands of button screw dies, the combination of a stationary machine frame, a die holder mounted for rotation in said frame and formed with a peripheral rim furnished with a plurality of angularly spaced peripheral slots, a grinding wheel spindle journaled to rotate about an axis parallel to that of said die holder, a support for said spindle, power means for rotating said spindle, a resiliently-actuated tooth pivoted in said machine frame in position to engage each of said notches to register said die holder in a plurality of spaced angular positions, means for moving said support to cause a predetermined relative movement be-

tween said spindle and said die holder in each of the angular positions of said die holder, a rotary feed handle, gearing connecting said feed handle to said die holder to rotate the latter about the axis of the die to produce the cutting feed during grinding, a one-way clutch interposed between said feed handle and said die holder to permit said die holder to turn forwardly while said feed handle is stationary, and an adjustable stop located to co-act with said feed handle to limit the maximum amount of the cutting feed during each of a plurality of grinding operations, each of said notches being shaped on one face to cause disengagement of said resiliently-actuated teeth during the rotation of said die holder by said feed handle in effecting each of said grinding operations.

14. In a machine for performing a plurality of grinding operations at spaced angular positions on a metal work-piece, the combination of a stationary frame, a work holder mounted for rotation on said frame and furnished with a plurality of angularly spaced peripheral notches, a grinding wheel spindle journaled to rotate about an axis parallel to that of said work holder, power means for rotating said spindle, a pantograph linkage provided with a tracing stylus, a support for said spindle mounted on one member of said pantograph linkage, a pattern support located in position to be traversed by said tracing stylus, a resiliently-actuated tooth pivoted in said machine frame in position to engage each of said notches to register said work holder in a plurality of spaced angular positions, a rotary feed handle, and gearing connecting said feed handle to said work holder to rotate the latter about the axis of the die to produce the cutting feed during each of the plurality of grinding operations.

15. In a metal grinding machine, the combination of a stationary machine frame, a work holder mounted for rotation and guided for axial reciprocation in said machine frame, a grinding wheel spindle journaled to rotate about an axis parallel to that of said work holder, a support for said spindle, power means for rotating said spindle, a cam shaft journaled in said machine frame, cams on said cam shaft co-acting with said work holder to effect reciprocation of same in said machine frame, means for moving said support to cause movement of said spindle along a predetermined path, and manual means for rotating said work holder to produce the cutting feed during grinding.

16. In a machine for grinding the lands of button screw dies, the combination of a stationary machine frame, a die holder mounted for rotation and guided for vertical reciprocation in said frame about the axis of a die carried in said die holder, a grinding wheel spindle journaled to rotate about an axis parallel to that of said die holder, a support for said spindle, power means for rotating said spindle, a horizontal cam shaft journaled in said machine frame, cams carried by said cam shaft and co-acting with said die holder to effect vertical reciprocation of same, means for moving said support to cause movement of said spindle along a predetermined path conforming to the profile to be ground, a rotary feed handle and gearing connecting said feed handle to said die holder to rotate the latter about the axis of the die to produce the cutting feed during grinding.

17. In a metal grinding machine, the combination of a work holder mounted for rotation, a grinding wheel spindle journaled to rotate about

an axis parallel to that of said work holder, a support for said spindle, compressed air motor having its rotor secured to said spindle, a conduit for supplying compressed air to said air motor, a manually-operated valve for controlling air flow through said conduit, means for moving said support to cause movement of said spindle along a predetermined path, and manual means for rotating said work holder to produce the cutting feed during grinding.

18. In a machine for grinding the lands of button screw dies, the combination of a die holder mounted for rotation about the axis of a die carried in said die holder, a grinding wheel spindle journaled to rotate about an axis parallel to that of said die holder, a compressed air motor having its rotor secured to said spindle, a conduit for supplying compressed air to said air motor, a manually-operated valve for controlling air flow through said conduit, a support for said spindle, means for moving said support to cause movement of said spindle along a predetermined path conforming to the profile to be ground, a rotary feed handle, and gearing connecting said feed handle to said die holder to rotate the latter about the axis of the die to produce the cutting feed during grinding.

19. In a metal grinding machine, the combination of a stationary machine frame, a work hold-

er mounted for rotation and mounted in said machine frame to slide transversely to its axis of rotation, means for locking said work holder in said machine frame after sliding into a predetermined position, a grinding wheel spindle journaled to rotate about an axis parallel to that of said work holder, a support for said spindle, power means for rotating said spindle, means for moving said support to cause movement of said spindle along a predetermined path, and manual means for rotating said work holder to produce the cutting feed during grinding.

20. In a machine for grinding the lands of button screw dies, the combination of a stationary machine frame, a horizontal slide carried in said frame, a die holder supported on said slide and mounted for rotation about the axis of a die carried in said die holder, a locking screw for locking said slide in a predetermined adjusted position in said frame, a grinding wheel spindle journaled to rotate about an axis parallel to that of said die holder, a support for said spindle, power means for rotating said spindle, means for moving said support to cause movement of said spindle along a predetermined path conforming to the profile to be ground, and manual means for rotating said die holder about the axis of the die to produce the cutting feed during grinding.

EDGAR BANNISTER.
